WRAPPING AND FOLDING MACHINES

Leslie Gordon Forster, Ealing, London, England, assignor to Forsters Machine Company Limited, Hayes, England, a corporation of Great Britain

Application January 2, 1953, Serial No. 329,295

8 Claims. (Cl. 53—224)

This invention relates to wrapping machines for covering articles with thin material such as paper, cellulose or the like of the kind in which the articles are moved at spaced intervals along the bed of the machine and the several wrapping and folding operations on each article are carried out in succession. The invention refers particularly to the general lay-out and direction of the bed, to the direction of progression through the machine of the articles to be folded and to associated constructional features.

I have disclosed in certain prior applications several constructions relating to the various characteristics of a machine of this kind having an approximately horizontal bed, the articles being moved by a conveyor along the bed, while the several operations of cutting off a length of wrapping material, tucking and folding the sides, and tucking and folding the ends are carried out. These applications include:

Conveyor means for moving the article along a bed as disclosed in U. S. A. patent specification No. 2,570,030.

Operation of the cutters—U. S. A. patent specification No. 2,586,462.

Feeding the thin covering material—U. S. A. patent application Ser. No. 262,126/1951, now U. S. Patent No. 2,722,275.

Final tucking and folding of the wrapping material—U. S. A. patent application Ser. No. 162,835/1950, now U. S. Patent No. 2,722,094. In U. S. A. patent specification No. 2,570,030, there is disclosed mechanism for moving articles in succession along a bed on which the articles are supported, the mechanism being located below the bed. The mechanism includes an endless chain running over sprockets or pulleys located adjacent the receiving and the delivery ends of the bed. The fingers are mounted pivotally on the chain and are projected upwardly through a longitudinal slot in the bed when they are travelling with the upper run of the chain, their angular position relatively to the chain being controlled by guides. The chain runs at the receiving end over a pulley and at the delivery end over a group of rotational elements such as sprockets or pulleys. The elements of the said group are so arranged that each finger (1) dwells for a short interval after reaching its end position, (2) is next withdrawn rearwardly for a short distance and (3) is then moved downwardly clear of the next following article after which it is carried rearwardly by the lower run of the chain to the receiving end of the machine.

In U. S. A. patent application Ser. No. 162,835/1950, now U. S. Patent No. 2,722,094, a series of folding and tucking operations of thin covering material applied to a rectangular article has been shown and described.

Each article together with a length of covering material is pushed by a finger along a closed passage formed by the bed, by two side folding plates, each in three parts, and by an upper retaining plate. During this movement, the parts of the covering material extending above and below the article are bent backwards by the upper plate and by an edge of the bed so that one part is folded

2

underneath and the other part above the article. The parts of the covering material extending sideways are similarly tucked in by the ends of the side folding plates leaving upper and lower wings or edges of covering material extending laterally. During further movement, downwardly inclined slots between two parts of each of the side folding plates turn down the upper edges of the covering material. Still further movements leads the upper edges of the covering material through upwardly inclined slots provided on each side by the side folding plates, whereby the lower edges of the covering material are folded upwardly. The foregoing operations are all in accordance with known practice.

The finger when it has moved the partially wrapped article into its end position, dwells for a short interval, is next withdrawn rearwardly for a short distance and is then moved downwardly clear of the next following article. The means for effecting such movements are disclosed in the aforementioned U. S. A. patent specification No. 2,570,030.

20 The final side tucking and end folding operations by which the article is completely wrapped are effected by side tuckers, while the packet is stationary, and by a flanged top-plate and a fixed bar or edge during movement of the packet downwardly relatively to the bed. The mechanism for effecting these final operations forms the subject matter claimed in the aforementioned U. S. A. patent application Ser. No. 162,835/1950, now U. S. Patent No. 2,722,094.

25 It is an object of the invention, in the construction of wrapping machines, to provide a bed along which flat or thin articles are pushed with an edge in contact with the bed by fingers having an operative face inclined backwards at an angle to the vertical to avoid instability of said article while tucking and folding operations are carried out.

30 Another object of the invention is the construction of wrapping machines in which the bed is inclined at a substantial angle to the horizontal and the articles to be wrapped are moved upwardly along the inclined bed by the moving fingers in opposition to a retarding force due to a component of the force of gravity in addition to frictional resistance.

35 It is also an object of the invention to provide a rectangular bed having a longitudinal slot therethrough in conjunction with fingers having an operative face above the bed inclined backwards at an angle to the vertical, the fingers extending through the said slot and being moved lengthwise of the bed by mechanism located thereunder.

40 It is also an object of the invention to provide wrapping machines in which articles to be wrapped are moved in succession upwards along a bed inclined at a substantial angle to the horizontal, means for feeding and cutting off lengths of covering material and for carrying out side folding operations are located along the bed and the final tucking and folding operations are effected when the partly wrapped article reaches the upper end of the bed.

45 A substantial angle of inclination of the bed such as 30° would in many applications introduce a sufficient gravitational retarding component. The additional resistance thus exerted to the movement of the articles ensures a steady progressive movement without any risk of jumping or other irregularity of movement.

50 A further object of the invention is the provision of better output lines. At the upper output end, for example, the wrapped articles may leave the inclined bed in a direction initially at right angles thereto.

55 A still further object of the invention is to facilitate the wrapping of thin articles such as wafers and enable flat rectangular articles to be partly supported by one edge on the inclined bed and also partly supported and moved along the bed by a finger or operating member of the conveyor engaging one of the flat or large faces.

The placing of the articles on edge with their smallest dimension parallel to the bed enables the fingers on the conveyor to be spaced more closely. The number of articles wrapped per minute may then be increased or the conveyor may be run more slowly.

A still further object of the invention is to facilitate the wrapping of articles of irregular shape. One straight edge only, not necessarily a flat surface, is required on an article of irregular shape. The article is pushed up the inclined bed by the conveyor finger engaging this straight edge or flat surface on which the final tucking and folding operations take place. With some articles of irregular shape, folders and tuckers could in some cases be dispensed with and other closing means provided; for example, means for gathering up the free ends of the wrapping material behind the article and thus closing the package. Inclined wrapping machines will in fact deal with a much wider range of different articles than horizontal machines.

A still further object of the invention is the provision of a substantially horizontal feed conveyor on which the articles are placed and then fed on to the lower end of the inclined bed along which they are moved upwardly by the fingers of the wrapping machine. Flat or thin articles are laid flat on the feed conveyor and when discharged therefrom are tilted forwardly with one edge in contact with the bed so that the flat surface of the article is then engaged by a backwardly inclined finger.

A still further object of the invention is the wrapping of jellies which are of a yielding, elastic consistency with a somewhat sticky surface to which the thin covering material adheres and which tends to adhere to the parts of the machine whether made of metal, plastic or other hard material. Such jellies are commonly in the shape of rectangular slabs in which the thickness of the slab is substantially less than either of the other dimensions and one of the large faces of the jelly is engaged by the surface of a finger of the main conveyor, a narrow side or end surface being supported by the inclined bed.

Some or all of the constructions disclosed in my above-mentioned prior applications could be utilised in this machine according to requirements.

In the embodiment of the invention shown by way of example in the accompanying drawings, the difficulties associated with the wrapping of jellies have been given special consideration. The machine in which these difficulties have been overcome will, however, be suitable for dealing with other articles particularly flat articles.

In the drawings:

Figure 1 shows a side elevation of the improved machine with a horizontal feed conveyor and delivery arrangements;

Figure 2 shows a part sectional side elevation of the horizontal feed conveyor and of guiding means for thin covering material;

Figure 3 shows a plan of Figure 2;

Figure 4 shows a side elevation of mechanism at the delivery end of the machine with tucker operating means and associated mechanism omitted; and

Figure 5 shows a view of the delivery end looking in the direction of the arrow A of Figure 4.

Referring first to Figures 1 to 3 of the drawings, the bed 1 of the machine is shown inclined at an angle of 30° to the horizontal and is supported on a base 2. The bed and the base may be integral with one another but preferably the bed is separate from the base and is bolted thereto. These parts may advantageously be fabricated from steel components. The bed carried a cutting and feeding assembly 3 for the cellulose or other covering material 14 such as is disclosed in our afore-mentioned U. S. A. patent specification Serial No. 2,586,462 and U. S. A. patent application Serial No. 262,126/1951, now U. S. Patent No. 2,722,275. The bed also supports the side folding apparatus comprising plates or guides 4 and the final tucking, folding and delivery mechanism

which may be such as is disclosed in our afore-mentioned application Serial No. 162,835/1950, now U. S. Patent No. 2,722,094.

The jellies or other articles 5 are moved upwards 5 along the inclined bed in succession by a series of fingers 11 carried by an endless chain main conveyor (not shown) such as is disclosed in our afore-mentioned U. S. A. patent specification No. 2,570,303. This main conveyor is located below the bed. All the operating components carrying out the cutting, feeding and wrapping operations are preferably driven from a common source of power.

The machine operators place the uncovered jellies flat 15 on a feed conveyor unit 6 shown in detail in Figures 2 and 3. This feed conveyor is preferably horizontal and is held in position by bolting it at one end 7 to the lower end of the inclined bed 1 and supporting it at the other end by an adjustable strut 8. The conveyor unit includes two longitudinal side plates 9 lying in vertical 20 planes and connected by cross members. Two side platforms 12 are supported on the outer sides of the side plates 9. The junctions between the side plates 9 and the platforms 12 are covered by strips 10.

The conveyor mounted between the side plates 25 includes two endless chains 13 each running over a driving sprocket 14, a rear end sprocket 15 which may be adjustable to tension the chain, a front sprocket or roller 16 and intermediate sprockets or rollers 17, 18 all supported from the adjacent side plate 9. The two chains 30 are driven in synchronism with the main conveyor chain through a chain 19 and sprockets 20, 21. The chains each carry a series of fingers 23 extending inwards towards one another so as to engage the packets and move them forward in succession.

During their movements forward, the jellies 5 move 35 over a runway composed of closely-spaced free-running rollers 24 mounted on and between two longitudinal angle section members 25 supported from the side plates 9 by cross members 26.

The jellies before leaving the rollers 24 are positioned 40 laterally by running them between two large diameter free-running side rollers 27 which are adjustable sideways to suit jellies or packets of any width within the limits of the machine. The peripheries of the side rollers are grooved circumferentially to reduce the risk of sticking. The rollers 24 may be arranged with their upper surfaces at a lower level than the chains 13. With this arrangement, the chains guide and prevent lateral spreading of the jellies. The side rollers 27 are then unnecessary.

The jellies next run over a series of closely-spaced free-running rollers 28 of smaller diameter, the last few rollers 45 29 providing a downward slope which tips the jellies forward into such a position that they can be engaged by a finger 11 of the main conveyor and carried upwards along the inclined bed. The end rollers 28, 29 are supported independently of the rollers 24 on the end of an arm 30, the other end of which is secured to cross members 31 extending between the side plates 9 of the conveyor unit.

During the first part of the upward movement along the inclined bed, the lower edge of each jelly runs over a further series of closely-spaced free-running rollers 32 which extend along the bed as far as the plane of movement of the covering material 14 downwards into the position in which a length is cut off, the lower end of this cut off length of covering material extending into the transverse gap 36 in the bed. Beyond this position, the lower supporting edges of the jelly are covered by the covering material and will slide more easily over the smooth metal surface of the bed so that rollers are no longer necessary to reduce the resistance to movement. The rollers 32 are arranged in two parallel series with a gap 33 between them. They are located within a wide opening 22 in the bed extending rearwardly or downwardly from the gap 36 and their upper surfaces stand 50 slightly above the upper surface of the bed. The rollers

32 rotate freely on spindles which are overhung inwardly towards one another from supporting members 34 carried by and running parallel to the bed 1 of the machine. The rollers in each series are held against movement lengthwise of their overhung spindles by a longitudinal retaining strip 35 engaging circumferential grooves in the rollers.

The upright part of the conveyor finger 11 is so shaped that the finger straddles the single row of end rollers 28, 29 as it moves into position to engage a jelly. The finger includes a flat rearwardly extending part 11a secured to the upper end of a narrow stem (not shown) which passes along the gap 33 as the jellies are moved forwards and then along the longitudinal slot 33a in the bed during further movement.

During their further movement upwards along the bed of the machine between the vertical side plates or guides 4 having inclined folding slots 37 of known type, the covering material at the sides is tucked in and folded downwards and upwards. The side plates 4 may be grooved leaving longitudinal projections to reduce friction and allow easier movement in view of possible deformation of the sides of the jelly slabs 5.

The top plate 38 closing the channel along which the slabs move may be made of light material, for example, a suitable plastic material, so that it may lift slightly if the jelly slabs bulge upwardly.

The thin covering material 14 is fed downwards in an inclined direction perpendicular to the bed 1 by the feed rollers 42 in the feeding and cutting assembly 3 as shown in Figures 2 and 3. In the present construction the covering material 14, after passing downwards between the cutters 43, bears lightly, due to the force of gravity, against guides 44 projecting upwards from the bed, the guides being located at opposite sides of the article so as to clear the article. When a length of material is cut-off, it is held by the front edge of the moving packet. The side guides 44 are generally perpendicular to the bed 1 but have an upper inclined leading-on part 45. The covering material 14 is thus prevented from sagging downwards towards the approaching article as it is fed across the space between the cutters 43 and the bed 1. A steady guided movement of the covering material thus takes place avoiding risks of wasters.

When each jelly reaches its final position just beyond the end of the bed, its lower edge bears upon two pivoted resiliently-supported tongues as disclosed in our aforementioned application Ser. No. 162,835/1950, Patent No. 2,722,094.

It is necessary, with the present inclined bed machine that the jelly 5 or other article shall be held against any tendency to tilt backwards or to stick to the main conveyor finger 11 when the finger is withdrawn. With this and other objects in view the central part of each finger is cut away leaving a space 49 into which a holding finger 50 may be moved before the conveyor finger 11 is withdrawn. The holding finger 50 and the mechanism operating it are shown in Figures 4 and 5.

The space 49 formed in the conveyor finger also possesses the advantage that it tends to counteract the tendency to lateral spreading or other distortion of the slab of jelly 5 during the operation of the machine, since the bulging of the jelly into the said space reduces the amount of bulging which would otherwise take place at the sides.

With the object of reducing sticking of the jelly to the metal or other material, the conveyor finger and the holding finger may be drilled at intervals, the holes 51 being preferably countersunk.

The holding finger 50 is carried on the bent lower end of an arm 53 secured at its upper end to a spindle 54 carried in a bearing 55 supported from the bed 1 by a bracket 56. The bracket 56 having stiffening ribs 57 is bolted to the sides of the bed of the machine. On one end of the pivot mounting is secured a short arm 60 connected by a link 58 to cam operating mechanism driven from the

main source of power such as an electro-motor through, for example, bevel gearing 59 so that it runs in properly timed relationship to the main conveyor and to the downward movement of the flange of the top plate 71. The cam 5 62 rotates with the shaft 63 on which it is mounted and the cam surface includes a part 64 of larger radius and a part 65 of smaller radius. A cam roller 66 carried on link 68 bears upon the cam surface and is kept in contact therewith by a tension spring 67. The forked end of the link 68 engages a roller 61 carried on the shaft 63 whereby the cam roller 66 is maintained in a position to engage the cam surfaces. The mechanism is shown in both its operative and inoperative positions. In the operative position shown in chain lines with the holding finger 50 engaging the face of the jelly, the cam roller 66 engages the part 65 of the cam surface of smaller radius, while in the inoperative position shown in full lines, the roller 66 engages the part 64 of the cam surface of larger radius and the holding finger 50 is held well clear of the following jelly or packet next to be dealt with. The inoperative time period is, of course, much longer than the very short operative period.

The partially wrapped packet, when in position for the final tucking and folding operations, is also held by adjustable side plates 69 and by an adjustable end plate 70. These plates are mounted and adjusted similarly to the plates carrying holding brushes as described in my afore-mentioned application Ser. No. 162,835/1950, Patent No. 2,722,094.

The wrapped packet is finally pushed downwards by the flanged top plate 71 carried by an arm 72 connected to a linearly guided member 73 and runs down a curved delivery path having rollers 74. The member 73 is guided vertically by four pairs of ball bearings 75 and is moved by mechanism, not shown, in timed relationship to other parts of the machine. The packets are guided onto the curved delivery path by a downward extension of the end plate 70 and by side guiding plates 76 which carry the side plates 69 and are supported by laterally adjustable members 77.

The mechanism at the delivery end of the machine is protected by side shields 78 as shown in Figure 1. These shields are omitted from Figure 4.

We claim:

1. Wrapping machine for covering flat or thin articles in succession with thin material comprising in combination; a bed inclined to the horizontal and having a longitudinal slot passing therethrough; fingers, extending through said slot, the operative face of each of said fingers extending above said bed being inclined backwards at an angle to the vertical to engage a flat face of said article; mechanism located below said bed and adapted to move said fingers lengthwise of the bed whereby each finger moves an article along the bed in opposition to a retarding force due to a component of the force of gravity and to frictional resistance between an edge of the article and the bed; means for feeding a strip of covering material towards said bed; means for cutting off a length of said material in front of said article; and means for carrying out tucking and folding operations thereafter.

2. Wrapping machines for covering flat or thin articles in succession with thin material as claimed in claim 1, comprising in combination therewith a substantially horizontal feeding conveyor including longitudinally spaced operating fingers for feeding the articles towards the lower end of the inclined bed, a series of closely-spaced freely-rotatable rollers upon which the articles run, an inclined series of closely-spaced freely-rotatable rollers at the delivery end of the feed conveyor adapted to tilt the articles forwardly in succession so that an edge of each article bears upon the inclined bed, in readiness for engagement by one of said backwardly inclined spaced fingers whereby the article is moved upwardly along the inclined bed.

3. Wrapping machine for covering flat or thin articles in succession with thin material as claimed in claim 1, comprising in combination therewith a substantially horizontal feeding conveyor comprising two parallel endless chains and longitudinally spaced conveyor fingers extending upwardly from the chains, a first series of closely-spaced freely-rotatable rollers between the chains over which rollers the articles are adapted to move, lateral extensions from the said conveyor fingers extending over the rollers whereby each article is moved forward, a second series of closely-spaced freely-rotatable rollers providing an inclined runway adapted to tilt the articles downwardly whereby an edge thereof engages the inclined bed, U-shaped surfaces on said backwardly inclined fingers adapted to move the articles upwardly along the inclined bed, the said U-shaped surfaces being adapted to straddle the said second series of rollers; and a third series of two parallel closely-spaced freely-rotatable rollers mounted with their upper surfaces slightly above the upper surface of the said bed so as to support the lowermost edge of the article until the said edge is covered by the wrapping material, the stems of the backwardly inclined fingers extending through a gap between the two sets of rollers of the said third series.

4. Wrapping machine for covering flat or thin articles in succession with thin material comprising in combination; a bed inclined at an angle to the horizontal; longitudinally spaced fingers each having a forward operative face inclined backwards at a substantial angle to the vertical and adapted to engage a flat face of, and partially support, an article; mechanism adapted to move said spaced fingers lengthwise upwardly along the bed; means for carrying out the several tucking and folding operations necessary to cover the article; a substantially horizontal feeding conveyor including longitudinally spaced operating fingers for feeding the articles towards the lower end of the said inclined bed, a series of closely-spaced freely-rotatable rollers upon which flat faces of the articles bear and an inclined series of closely-spaced freely-rotatable rollers at the delivery end of the feed conveyor adapted to tilt the articles forwardly so that an edge of the article bears upon the inclined bed, each article being thereby positioned so that a flat face thereof may be engaged by one of said spaced backwardly inclined fingers whereby the article is moved upwardly along the inclined bed.

5. Wrapping machine for covering flat or thin articles in succession with thin material comprising in combination; a bed inclined at an angle to the horizontal; longitudinally spaced fingers each having a forward operative face inclined backwards at a substantial angle to the vertical and adapted to engage a flat face of, and partially support, an article; mechanism adapted to move said spaced fingers lengthwise upwardly along the bed; means for carrying out the several tucking and folding operations necessary to cover the article; and a holding finger engaging the rear face of each article over an area not covered by the operating surface of a longitudinally spaced finger while the final tucking and folding operations are carried out.

6. Wrapping machine as claimed in claim 5, comprising mechanism which moves the holding finger between its operative and inoperative positions in correct relation to the movements of the backwardly inclined fingers.

5 7. Wrapping machine for covering flat or thin articles in succession with thin material comprising in combination; a bed inclined to the horizontal and having a longitudinal slot passing therethrough; fingers extending through said slot, the operative face of each of said fingers extending above said bed being inclined backwards at an angle to the vertical to engage a flat face of said article; mechanism located below said bed and adapted to move said fingers lengthwise of the bed whereby each finger moves an article along the bed in opposition to a retarding force due to a component of the force of gravity and to frictional resistance between an edge of the article and the bed; means for feeding a strip of covering material towards said bed; means for cutting off a length of said material in front of said article; a backwardly inclined guide for the strip of covering material located on each side of the inclined bed, the guides being so spaced apart as to engage and support the sides of the strip to prevent sagging thereof due to the inclination of the said strip, a clear passage being left between the guides for the movement of the article upwardly along the bed of the machine.

20 8. Wrapping machine for covering flat or thin articles in succession with thin material comprising in combination; a bed inclined at an angle to the horizontal; longitudinally spaced fingers each having a forward operative face inclined backwards at a substantial angle to the vertical and adapted to engage a flat face of, and partially support, an article; mechanism adapted to move said spaced fingers lengthwise upwardly along the bed; means for carrying out the several tucking and folding operations necessary to cover the article; a substantially horizontal feeding conveyor including longitudinally spaced operating fingers for feeding the articles towards the lower end of the said inclined bed, a series of closely-spaced freely-rotatable rollers upon which flat faces of the articles bear; and a runway formed by a series of freely mounted transverse rollers extending upwardly along part of the bed and having their upper surfaces slightly above the plane of the bed whereby the lowermost edge of each article is supported by said rollers during part of its movement along the bed.
